UNITED STATES PATENT OFFICE.

CHARLES W. GLIDDEN, OF LYNN, ASSIGNOR TO JAMES W. BROOKS, TRUSTEE,
OF CAMBRIDGE, MASSACHUSETTS.

HEEL-TRIMMING MACHINE.

SPECIFICATION forming part of Letters Patent No. 410,358, dated September 3, 1889.

Application filed February 18, 1889. Serial No. 300,274. (No model.)

To all whom it may concern:

Be it known that I, CHARLES W. GLIDDEN, of Lynn, county of Essex, State of Massachusetts, have invented an Improvement in Heel-trimming Machines, of which the following description, in connection with the accompanying drawings, is a specification, like letters on the drawings representing like parts.

This invention has for its object to improve and simplify the construction and operation of that class of heel-trimming machines employing rotary cutters.

The machine herein to be described has a cutter the blades of which are simultaneously adjustable, and the rotary cutter has combined with it a rest for the edge of the heel being trimmed, the said rest being of peculiar construction and being adjustable in a peculiar manner. The machine has connected with it an exhaust-fan, and the trunk leading from the exhaust-fan to the cutting-tool has a cover hinged to the trunk opposite the said tool. The machine herein to be described has two shafts, one for a cutter and the other for a grinding-wheel, both the cutter and grinding-wheel having co-operating with them hoods and wind-trunks leading to them in different radial planes from a common exhaust-fan.

The particular features in which my invention consists will be hereinafter further described, and specified in the claims at the end of this specification.

Figure 1 in elevation represents a heel-trimming machine embodying my invention, the rotary cutter, together with the tread-guard and counter-guard and the edge-rest, being removed. Fig. 2 is a vertical section in the line α of one of the hangers for one of the rotary shafts. Fig. 3 is a front end view of the counter-guard and its supports and the rotary cutter, the tread-guard and edge-rest removed from Fig. 1. Fig. 4 is a view of Fig. 3, looking at it in the direction of the arrow 2, the cutter-head being broken out to better show its construction. Fig. 5 is a detailed front elevation of the cutter-head and tread-guard. Fig. 6 is a longitudinal cross-section

of Fig. 5. Fig. 7 is two views showing the grinding-wheel. Fig. 8 is a detail of the yoke 50 to which the carriage is pivoted, and Fig. 9 is a detail showing one of the cutter-blades detached.

The base A of the machine supports a column A', having a top plate A², to which is attached by suitable nuts A³ A⁴ the shanks of suitable hangers A¹², forked at their lower ends to support boxes, as A¹³, there being two such boxes for the cutter-shaft a, and also the shaft b. The top plate A² has posts A⁵, which support a work-table A⁶, provided, as herein shown, about its edge with a rim. The column A' is made hollow, and the base A has erected upon it suitable bearing-stands A⁷, which support the driving-shaft A⁸, driven by power in any usual manner, the said shaft having fast upon it two belt-pulleys a' and b', the pulley a' receiving a belt which is passed over a pulley a² on and so as to rotate the cutter-shaft a, while the pulley b' receives a belt which is passed over a pulley b² on and rotates the shaft b. The shaft A⁸ in practice will have a third pulley, (not shown) which by belt will rotate the shaft B of the exhaust-fan, the case of which is shown at B', it having a 75 foot which is bolted upon a stand B³ of the column.

The shaft b at its front end will in practice have secured to it a grinding-wheel b³, (shown separately in Fig. 7,) covered with sand or emery-paper or cloth to constitute an abrading-surface, the said wheel being used to finish the edges of the heel after the heel has been trimmed.

The wheel b³ will have arranged in close proximity to and preferably somewhat surrounding it the upper end of a wind-trunk b⁴, having a hinged door or cover b⁵ opposite the end of the shaft b. The lower end of the said wind-trunk is joined to one side of the 90 case of the exhaust-fan.

The top plate A² of the machine has bolted to it a guide-bracket C, (see Figs. 1 and 4,) having a dovetailed or other shaped guide-groove, which receives in it the shank c of a block c', in 95 which slides a U-shaped yoke 4, (shown sepa-

rately in Fig. 8 enlarged,) the said yoke having a substantially longitudinal slot 5, the said slot receiving in it a pivot-pin 2 (shown by dotted lines in Figs. 3 and 4) of a carriage c^3 , 5 to which in turn is secured the rand or counter guard c^3 , composed, as herein shown, of a hoop or band of metal, as steel, suitably bent and dished, and suitably attached at its ends, by screws or otherwise, to the said carriage, 10 the rand-guard being opened opposite the end of the cutter-shaft and cutter.

The shank of the carriage farthest from the guard c^3 is acted upon by a spring c^5 , secured to the sliding yoke 4, so that the said spring 15 normally acts to keep the rand or counter guard pressed toward the face of the cutter d , but yet permits the said counter-guard to be moved angularly with relation to the said cutter to uncover, as has been described in 20 several other pending applications made by me, more or less of the edges of the blades of the cutter when trimming about the rear part of the heel.

I have combined with the yoke 4 an adjusting-screw c^{10} , so that the said yoke may be adjusted more or less for a large or small cutter without varying the relative condition of the said spring, so that it acts substantially the same with different-sized cutters.

30 The shaft a is surrounded by a tread-guard e of usual construction, and just outside the tread-guard the shaft is squared, as shown at 8, Figs. 1 and 6, to receive upon it the head 9, which, like the head 10, is mounted upon a 35 squared part 12 of the said shaft a , and the head 10 is slotted, as at 13, (see Fig. 5,) at three different places to receive the ends of like pins 14, which are also extended through nearly-radial slots 15 (shown by dotted lines, 40 Fig. 5) in the head d , the said pins also passing through and fitting round holes in the ears d^2 of the cutter-blades d^3 .

The cutter herein shown forms the subject-matter of application, Serial No. 283,197.

45 The construction of the cutter herein shown is such that when the nut 17 is loosened and the screw 18 partially withdrawn the cutter-head may be moved or turned slightly about the shaft a , causing the ends of the pins 14 to 50 travel longitudinally in the slots 13, the said pins so moved causing the cutter-blades to be moved outwardly simultaneously to compensate for wear in grinding and maintain a standard size for the cutter.

55 The bearing 19 for the shaft a has clamped and fixed upon it a slotted arm 20, having adjustably secured to it by a set-screw 22 a curved or sector-like arm 23, upon which is adjustably mounted a shoe 26, the arc in 60 which the shoe 26 is adjustable being that of a circle described from the center of the cutter-shaft a . The shoe 26 is held in adjustable position by a set-screw 27, and the circular path of the shoe is determined by a

circular tongue and groove between the parts 65 23 and 26. The shoe 26 has connected to it by a set-screw 28 the edge-rest m , upon which in practice will rest the edge of the heel being trimmed.

The drawing Fig. 3 has been marked "top 70 side" to show the working position of the parts.

The case of the exhaust-fan has a trunk portion E , in which is loosely fitted or entered a trunk portion f , the upper portion f^2 75 of which, as shown, surrounds the shaft a , and is secured to the top plate a^2 by a screw 24.

The trunk portion f has pivoted to it at 25 a cover portion f^3 , having a fastening f^4 , 80 which, when the cutter-head and its co-operating cutters and guides are in place, is thrown up from its position, Fig. 1, to inclose the same as in a hood, so that the chips cut from the heel by the rotating cutter are exhausted 85 into and taken away by the exhaust-fan.

I claim—

1. In a heel-trimming machine, the block c' , the carriage c^3 , and its rand-guard composed of a band of thin sheet metal dished and bent 90 around, substantially as shown and described, and attached only at its opposite ends to the said carriage, combined with the supporting-yoke, in which the said carriage slides to operate, substantially as described.

2. In a heel-trimming machine, the combination, with the heel-trimming cutter, its shaft, and the edge-rest m , of supports for the said edge-rest, whereby it may be adjusted not only radially toward and from the center 100 of the said shaft, but also in the arc of a circle about the said shaft, substantially as described.

3. In a heel-trimming machine, the fixed arm 20, and the radially-adjustable extension 105 23, combined with a shoe 26, made adjustable thereon in the arc of a circle described about the center of the said cutter-shaft, and with a rest, as m , for the edge of the heel, substantially as described.

4. In a heel-trimming machine, the block c' , the independent sliding yoke 4 therein, a carriage movable in the said yoke, and a rand or counter guard attached to the said carriage, combined with the spring c^5 , carried by 115 the said yoke and acting upon the said carriage to keep it normally pressed toward the said cutter, substantially as described.

5. In a heel-trimming machine, the block c' , the independent sliding yoke 4 therein, a carriage movable in the said yoke, and a rand or counter guard attached to the said carriage, combined with the spring c^5 , carried by 120 the said yoke and acting upon the said carriage to keep it normally pressed toward the said cutter, and with an adjusting-screw to act upon the said yoke, substantially as described.

6. In a heel-trimming machine, the combination, with the column supporting the trimming mechanism, of a rotary shaft carrying a rotary cutter, bearings for the said shaft, 5 and a work-table A⁶, arranged horizontally above and parallel to the shaft carrying the cutter, substantially as described.

In testimony whereof I have signed my name to this specification in the presence of two subscribing witnesses.

CHARLES W. GLIDDEN.
